UNITED STATES PATENT OFFICE.

JOHN E. OSTLINE, OF LIVERPOOL, AND THOMAS M. EDMUNDS, OF KINGS LYNN, ENGLAND, ASSIGNORS, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed December 7, 1925, Serial No. 73,556, and in Great Britain January 23, 1925.

This invention relates to telephone systems and is particularly concerned with improved circuit arrangements for automatic switches used in such systems and one object of the invention is the production of new and improved circuit arrangements for transmitting a busy tone to a calling subscriber and a busy flash to an operator when all the lines of a group, are engaged, and for recording the number of times all the lines of a group are busy.

Certain features of the invention are applicable to connector switches as well as selector switches. According to one feature of the invention circuit arrangements are provided whereby the switch magnet which responds to impulses dialled by a calling party is prevented from operating when all the lines of a group are busy should impulses be transmitted at this time.

Another feature of the invention concerns an improved arrangement for connecting battery potential to a speaking conductor to indicate the busy condition of a line or group of lines so that there is no difference of potential between the speaking conductors during the transmission of a busy flash signal.

A further feature of the invention concerns improved apparatus for busy flash and tone circuits which is common to a plurality of switches, the busy flash and busy tone circuits being connected to common conductors over alarm devices and means are inserted in the common conductors so that a fault on any conductor can be readily located by separating said conductors.

Some examples of the invention are shown in the annexed drawings, in which:

Figs. 1 and 6 show the improved circuit arrangements for a Strowger selector switch.

Fig. 2 shows an improved busy flash circuit using one common busy conductor per exchange, and

Fig. 3 shows a similar busy flash circuit using individual transformers per switch group instead of a common conductor per exchange.

Fig. 4 shows a modification using one conductor common to the exchange, while

Fig. 5 shows a modification of the arrangement shown in Fig. 4 using one transformer per group of switches.

Fig. 7 shows a modification of the busy tone and busy flash apparatus for use in connec-

tion with selectors such as the selector S¹, Fig. 6.

A description will first be given of the operation of the selector S, Fig. 1.

As soon as the selector S is taken into use by a calling party, line relay A energizes over the following circuit: battery, upper winding of relay A, back contacts and armature D¹ of switch relay D, negative line conductor, over the calling party's loop, positive line conductor, armature D² of switching relay D and its back contact, lower winding of relay A, eleventh cam spring Y and its back contact, common conductor 4, secondary winding of the dial tone transformer DT to earth. Relay A upon energizing completes at A¹ a circuit for slow release relay B. Relay B upon energizing earths the release trunk conductor P at B¹ and at B² prepares a circuit for the vertical magnet VM. Relay C responds to impulses generated by the calling party and at the back contact of A¹ repeats them to the vertical magnet VM over the circuit: earth, A¹, D³, B², through the slow series relay C to vertical magnet VM and battery. Relay C energizes in series with the vertical magnet and being slow to release remains operated throughout the series of impulses, and at C¹ opens one point in the circuit of rotary magnet RM and prepares a circuit for stepping relay E.

By the operation of the vertical magnet VM, the wipers 1, 2, and 3 of the selector S are raised opposite to the desired set of bank contacts. Upon the first vertical step, the off normal contacts ON and ON¹ close. By the closure of contacts ON the circuit, from earth, B¹, C¹, ON, E, to battery, is completed, thereby operating the stepping relay E. Relay E upon energising prepares a circuit at E¹ for rotary magnet RM and at E² completes a locking circuit for itself. The off normal contacts ON¹ prepare a circuit for the release magnet RM¹.

At the end of the series of impulses transmitted to the vertical magnet VM, slow series relay C releases and at the normally closed contacts controlled by C¹ completes a circuit for the rotary magnet RM. By the operation of the rotary magnet RM, the wipers 1, 2, and 3, are rotated in search of a free trunk. The interrupter springs R¹ break at the completion of each rotary step and open the locking circuit for relay E.

whereupon relay E de-energizes and opens a circuit of the rotary magnet at E¹. If the bank contact engaged by its wiper 3 is busy, switching relay D will be short circuited 5 and relay E again operates with the result that the rotary magnet is again energized. When the test wiper 3 encounters a free test contact switching relay D will not be short circuited and will energize in series with 10 stepping relay E over off normal contacts ON, rotary interrupter springs R¹, winding of relay D to the earthed test conductor P. Switching relay D upon energizing, disconnects the windings of line relay A from the line conductors at D¹ and D², and at D⁴ connects the test wiper 3 to the test conductor P, and at D³ opens a point in the vertical magnet circuit. Shortly after the de-energization 15 of line relay A, releases relay B de-energizes and closes at B² a point in the circuit for the release magnet RM¹.

The release of the connection is brought about by the removal of guarding potential from the conductor engaged by test wiper 3 which results in the de-energization of 25 switching relay D. Relay D upon de-energizing completes at D³ a circuit for the release magnet which includes the back contact of A¹, back contact of D³, back contact of B² and off normal springs ON¹.

Assuming now that all the lines in the selected level are busy, the eleventh step cam springs V, W, X, Y and Z will be operated on the eleventh rotary step. The Z springs 35 complete the following circuit for the busy relay BR, Fig. 2: earthed test conductor P, cam spring Z and its front contact, common conductor 6, busy relay BR (which is common to a group of selectors), busy cam springs BCS (which are common to the exchange) to battery.

The cam springs Y connect the lower winding of relay A to the common conductor 5 which is intermittently connected alternately 45 to battery through relay R and to earth through the low resistance winding of the busy tone transformer BT by the busy cam springs BCS. The cam springs V and W short circuit the springs D¹ and D² of the 50 switching relay D to maintain an energizing circuit for relay A, while the cam springs X connects earth to the conductor 7.

By the operation of the common busy relay BR, the conductors 7 and 8 which are individual to the selector S are connected together and earth is extended over conductor 8 to hold relay B energized independently of the contacts A¹ of the line relay A.

Returning now to the position where earth 60 is encountered on the tenth bank contact by test wiper 3, it will be seen that this earth potential completes a circuit for stepping relay E over the interrupter contacts R¹ and that relay E connects earth to the test wiper 65 3 at E², and also that at E¹ a circuit is closed

for the rotary magnet RM to move the wipers 3 into engagement with the eleventh contact P¹ to which the over-flow meter OFM is connected. The earth connected up at E² will operate the meter OFM before the rotary 70 interrupter springs R¹ open as these springs are arranged to open at the end of the rotary step and the meter will record the number of times the selector S finds all the lines of a group busy. The opening of the interrupter 75 springs R¹ will cause relay E to de-energize and the removal of earth at E² will allow the switching relay D to energize in series with relay E. Relay E however, is not energized in this circuit on account of the high 80 resistance of the relay D. Relay D, upon energizing, will operate its armatures D¹, D², D³, and D⁴. The operation of the armatures D¹ and D² will have no effect on line relay A as these contacts are short circuited by the 85 cam springs V and W. The armature D⁴ disconnects the test wiper 3 from one side of the switching relay D, while armature D³ opens a point in the circuit of the vertical magnet VM so that in case the calling party 90 should dial when all the lines of a group are busy, the vertical magnet VM will not be operated.

If the calling subscriber is at an automatic substation, the busy tone current which is 95 connected to the positive speaking conductor over the circuit: earth, secondary winding of busy tone transformer BT, busy cam springs BCS, common conductor 5, eleventh cam springs Y, lower winding of relay A, eleventh 100 cam spring W to the positive talking conductor, will indicate that the wanted line is busy.

The calling subscriber upon hearing the busy tone will replace his receiver and bring about the de-energization of relay A. Relay 105 A will open one point in the circuit of relay B at A¹ and when the busy cam springs BCS are operated to disconnect battery from relay BR the latter relay will de-energize and open the locking circuit for relay B for a period 110 long enough to allow relay B to release. Relay B, upon releasing, will open the circuit of the switching relay D at B¹ and switching relay D will complete a circuit for the release magnet at D³. If the calling party is an operator at a manual exchange, the battery 115 through relay R which is intermittently connected to the positive talking conductor will flash a supervisory signal at the operator's position over the circuit: battery, relay R, 120 busy cam springs BCS, common conductor 5, eleventh step cam springs Y, lower winding of relay A, eleventh step cam spring W to the positive speaking conductor.

Referring now to Figure 3, a busy tone and 125 busy flash circuit is shown using a transformer for each group of switches instead of one busy common per exchange as in Fig. 2. This arrangement has the advantage that in the event of conductor 5 being permanently 130

earthened, it would not render the whole of the exchange busy flash arrangements inoperative. The relay BR¹, Fig. 3, corresponds to the relay BR, Fig. 2, and the conductors 4¹, 5¹, 6¹, 7¹, and 8¹ to the conductors 4, 5, 6, 7 and 8, respectively, of Figure 2. The additional equipment in Fig. 3 comprises the busy flash transformer BFT and the three springs 10 on relay BR¹. One side of the primary winding of the busy flash transformer BFT is connected to earth direct and the other side to earth through the low resistance winding of busy tone transformer BT¹ which is common to the exchange. The secondary of the transformer is earthed at its middle point. One secondary winding is common to one group of switches and the other secondary winding is common to another group. The contact springs 10 of relay BR¹ alternately connect up busy tone and battery to common conductor 5¹ as relay BR¹ is intermittently operated by the interrupter cam IC which is common to the exchange.

Referring now to Fig. 4 an alternative busy flash and busy tone arrangement is shown together with the line and release relays of the selector switch. The line relay A¹ and release relay B¹ correspond to the relays A and B of the selector S and the eleventh step cam springs Y¹ and X¹ correspond to the eleventh step cam springs Y and X, while the busy cam springs BCS¹ correspond to the springs BCS, Figure 2, and as before are common to the exchange. A busy tone transformer BT¹ is provided which is also common to the exchange. It will be seen that the release relay B¹ is provided with two windings. The lower winding is a locking winding which is energized over the eleventh cam springs X¹, while the eleventh cam springs Y¹ connect the lower winding of the line relay A¹ to the common busy conductor which is alternately connected to battery and busy tone by the cam springs BCS¹. The auxiliary winding on relay B¹ is to prevent the relay from being locked up over the common conductor 12. It will be noted that with the arrangement shown in Fig. 4 the conductors 5, 6 and 7 and the relay BR are not required and moreover the operated cam spring Z may be eliminated also.

Referring now to Figure 5, an alternative busy flash and busy tone arrangement is shown which is similar to Fig. 4, except that a busy tone transformer BT² is provided for each group of switches instead of one transformer per exchange. The eleventh step cam springs Y² and X² are connected up as in Figure 1, and a busy relay BR² is provided which is controlled by the busy cam springs BCS². The transformer BT² is provided with a split secondary winding similar to the transformer BFT, Figure 3.

A description will now be given of the selector S¹, Figure 6, in conjunction with the

busy flash and busy tone apparatus shown in Figure 7.

Referring now to Figure 7, the apparatus below the dot and dash line comprising the dial tone machine DT¹, earth alarm relay EAR, common interrupter C¹ and the common busy tone transformer CBT is common to the whole exchange. The apparatus shown above the dot and dash line comprising the alarm relay EAR¹ the busy relay BR² and the busy tone transformer BT² are common to a group of selectors of the type shown at S¹, Fig. 6.

When the selector S¹ is taken into use the line relay AR energizes over the circuit: battery, upper winding of AR, 21, 20, - speaking conductor, calling loop, + speaking conductor 23, 24, lower winding of AR, 11th step cam spring 25 and its resting contact, dial tone conductor DT, secondary winding of dial tone machine DT¹ to earth. Relay AR upon energizing, completes the following circuit for release relay BR: earth, 28, 29, 30, lower winding of relay BR to battery. Release relay BR, upon energizing, earths the release trunk RT at 32 and at 33 further opens the circuit of release magnet Z. Relay AR responds to impulses transmitted over the - and + speaking conductors and at armature 29 repeats them to the vertical magnet V over the circuit: earth, 28, 29, 31, 33, 34, 26, relay CR, V, battery. By the operation of the vertical magnet V the wipers PW, - W and + W are raised step by step and come to rest opposite a level of bank contacts corresponding to the impulses received. Relay CR energizes in series with the vertical magnet V and being slow to release remains energized throughout the vertical movement. At armature 36, relay CR closes in conjunction with off-normal contacts N, which close on the first vertical step, a circuit from earthed release trunk RT for stepping relay ER. Stepping relay ER accordingly energizes and closes a locking circuit for itself at armature 40, and at armature 39 prepares a circuit for the rotary magnet R.

At the end of the vertical movement, slow relay CR de-energizes and closes the rotary magnet circuit at contacts 37-38. Rotary magnet R now energizes and advances the wipers PW, - W and + W into engagement with the first set of bank contacts in the selected level, and, near the end of its stroke, opens at interrupter contacts 41 the circuit of stepping relay ER, whereupon stepping relay ER de-energizes and opens the circuit of rotary magnet R at armature 39. Rotary magnet R now de-energizes and closes its interrupter contacts 41 again.

The further operation now depends upon whether the trunk terminating in the first set of bank contacts is busy or idle. In case the trunk is idle, switching relay DR energizes, seizing the trunk. Assuming on the

other hand that the trunk is busy, switching relay DR being short circuited by the earth potential encountered on the busy test contact by test wiper PW, does not energize, and the 5 stepping relay ER energizes from the same earth potential and again closes the rotary magnet circuit at armature 39, whereupon the rotary magnet R energizes again and advances the wipers another step. This alternate operation of stepping relay ER and 10 rotary magnet R continues as described until an idle trunk is reached. When an idle trunk is found the rotary magnet R de-energizes and closes its interrupter contacts 41 after having advanced the switch wipers into 15 engagement with the idle trunk. The switching relay DR, being no longer short circuited, energizes over the following circuit: earth, 32, RT, DR, normally closed 11th step cam 20 springs controlled by spring 27, 41, N, ER to battery. Stepping relay ER does not energize in this circuit on account of the high resistance of switching relay DR. Upon energizing switching relay DR disconnects earth 25 from armature 29 of line relay AR at armature 28, thereby opening the circuit of release relay BR; opens the test circuit and prepares the holding circuit at armature 43; and at armatures 20 and 23 disconnects the incoming 30 line conductors from line relay AR and extends them by way of wipers - W and + W to the line relay of the next switch. The line and release relays of the next switch now energize and prepare the switch for operation 35 in the usual manner, feeding earth potential back over wiper PW before the slow release relay BR falls away.

The release of the switch S^1 is brought about by the calling party hanging up his receiver and thereby causing the final selector in use to release and remove earth from the release trunk RT. The removal of earth from the release trunk RT brings about the de-energization of switching relay 40 DR. Relay DR upon de-energizing completes at armature 28 the following circuit for release magnet Z; earth, 28, 29, 31, 33, 35, N ^{1} , Z to battery. Magnet Z restores the switch to normal position, the energizing circuit for magnet Z being opened by the off-normal contacts N ^{1} when the switch shaft is in normal position.

Returning now to where the rotary magnet R is hunting for an idle line and assuming that all the lines of the selected group are busy, magnet R will advance the test wiper PW into engagement with the 11th step contact 45, and the + and - wipers to an open position. When the rotary magnet R makes the 11th step the 11th step cam springs 25, 26 and 27 are operated.

By the operation of cam springs 27 switching relay DR is short circuited. The momentary connection of earth potential to conductor 60 46 will not cause the operation of relay

ER as the interrupter contacts 41 are opened at this time. The operation of spring 25 disconnects the lower winding of line relay AR from earth via the dial tone conductor DT and connects it to the busy common conductor BC which is intermittently connected to earth and battery alternately. The operation of spring 26 prepares a circuit for the upper winding of release relay BR, and this circuit includes the hold common lead HC. 70

Referring now to Fig. 7 it will be seen that the busy relay BR ^{3} is intermittently energized and de-energized by the common interrupter C ^{1} which is arranged to connect battery and earth alternately to relay BR ^{3} . The 80 battery and earth potentials are arranged to be connected for 0.75 of a second and disconnected for 0.75 of a second. 75

Assuming that the common interrupter springs are in the position shown battery potential will be connected to the busy common conductor BC through the alarm fuse f, upper low resistance winding of the alarm relay EAR ^{1} , armature 52, armature 60, testing link l ^{4} . Battery potential will also be connected to the hold common lead HC, over armature 61 and testing link l.

The battery potential on conductor BC is connected to the positive speaking conductor over the following circuit and serves to flash 95 a supervisory signal when the calling party is an operator; battery, fuse f, upper winding of relay EAR ^{1} , 52, 60, l ^{4} , conductor BC, working contact and cam spring 25, lower winding of line relay AR, 24, 23, + speaking 100 conductor.

The substitution of battery potential for earth potential on the lower winding of relay AR will cause the latter to fall away and open the circuit of release relay BR. Relay BR being slow to release is now maintained energized by its upper winding over the following circuit: battery, fuse f, contact 61 of BR ^{3} , lead HC, upper winding of BR, working contact and cam spring 26, 34, 33, 31, 110 29, 28, to earth. It will be seen that battery potential is connected to the + and - speaking conductors through the upper and lower windings of line relay AR and since these windings are alike there will be no difference 115 of potential between the speaking conductors during the busy flash period. 115

When the common interrupter springs are operated relay BR ^{3} will be short circuited by the battery potential through relay EAR and the hold common lead HC will be disconnected and the busy common lead BC connected to earth through the secondary winding of the busy tone transformer BT ^{1} . The line relay AR will not be de-energized under these 120 conditions and release relay BR will be maintained operated over its lower winding. A busy tone current will now be connected to the speaking conductor over the following circuit: secondary winding of busy tone 125 130

transformer BT³, normally closed left hand armature of relay BR³, conductor BC, working contact and cam spring 25, lower winding of line relay AR, 24, and 23 to the speaking conductor. The calling party in this case will therefore receive a busy tone signal. The release of the switch S¹ in either case is brought about by the calling party opening the loop at the calling end across the + and 10 — speaking conductors whereupon line relay AR de-energizes and opens the circuit for release relay BR which de-energizes and removes earth from the release trunk RT at 32 and at 33 completes the following circuit 15 for release magnet Z: earth 28, 29, 31, 33, 35, N¹, Z. By the operation of release magnet Z the switch wipers, off normal contacts and cam springs will be restored to normal.

The earth alarm relays EAR and EAR¹ 20 and EAR² are provided to give an alarm in case the common conductors IC, BC or HC should become earthed. It will be readily seen that an earth on conductor IC will bring about the energization of relay EAR which 25 at contacts 50 completes any suitable alarm circuit. This fault can be readily located by removing the links l⁸ and l⁹.

An earth on conductor BC will cause the fuse f to blow and complete an alarm circuit 30 in known manner. An earth on the speaking conductor will not cause the fuse f to blow, but instead the alarm relay EAR¹ will operate over its upper winding and lock up over both windings and complete at 51 a circuit 35 for lamp L and alarm relay EAR². The exchange attendant seeing the lamp L glowing can locate the fault by removing the links l⁴ to l⁷. An earth on the common lead HC will cause the fuse f to blow and complete an alarm circuit, this fault can be 40 readily located by removing the links l to l³. Should the common busy tone lead BT⁵ become connected with battery potential the fuse f¹ will blow and complete an alarm circuit, this fault being readily located by removing the links l¹⁰ and l¹¹.

Having now particularly described and ascertained the nature of our said invention and in what manner the same is to be performed, we declare what we claim is:—

1. In a telephone system, a selector switch having a line relay controlled over an incoming talking conductor, a primary magnet controlled by the line relay, a secondary magnet for operating the switch to select an idle trunk, and means controlled by the secondary magnet and independent of the line relay for preventing the line relay from energizing the primary magnet, while maintaining the control of the relay over the incoming talking conductor.

2. In a telephone system, a selector switch having a line relay controlled over an incoming talking conductor, a primary magnet controlled by the line relay for selecting

a group of trunks, a secondary magnet, and means controlled by the secondary magnet responsive to a busy group of trunks being selected by the primary magnet for preventing the line relay from energizing the primary magnet while maintaining the control of the relay over the incoming talking conductor.

3. In a telephone system, a plurality of automatic switches, each switch having two incoming talking conductors and a line relay, a source of potential connected to both incoming talking conductors of each switch through the winding of the line relay of the switch, means common to all of the switches 75 and effective upon the occurrence of predetermined conditions in any of the switches for periodically connecting one of the talking conductors of the switch in which those conditions occur to a point at the same potential as that of the other conductor.

4. In a telephone system, a plurality of automatic switches, each switch having two incoming talking conductors and a line relay, a source of potential connected to both incoming talking conductors of each switch through the winding of the line relay of the switch, means common to all of the switches and effective upon the occurrence of predetermined conditions in any of the switches 90 for periodically connecting one of the talking conductors of the switch in which those conditions occur to a point at the same potential as that of the other conductor, said connection being made through a winding 100 on the line relay of the switch in which those conditions occurred.

5. In a telephone system, a plurality of automatic switches, each switch having two incoming talking conductors and a line relay, a source of potential connected to the incoming conductors of each switch through the winding of the line relay of the switch, each switch having accessible thereto a plurality of groups of trunks, means common 105 to all of the switches and effective when any switch encounters a busy group of trunks for periodically connecting one of the conductors of the switch that encounters the busy group of trunks to a point at the same 115 potential as is the other conductor of that switch.

6. In a telephone system, a plurality of automatic switches, each switch having two incoming talking conductors and a line relay, a source of potential connected to the incoming conductors of each switch through the winding of the line relay of the switch, each switch having accessible thereto a plurality of groups of trunks, means common 120 to all of the switches and effective when any switch encounters a busy group of trunks for periodically connecting one of the conductors of the switch that encounters the busy group of trunks to a point at the same potential as 125

130

- is the other conductor of that switch, said connection being made through a winding of the line relay of the switch.
7. In a telephone system, a switch having two incoming talking conductors, a line relay having two windings, one of which is connected to one conductor and the other winding connected to the other conductor, the other ends of the two windings being connected to opposite poles of a source of potential, means for periodically connecting one of the conductors to a point at the same potential as is the other conductor, said connection being made through a winding of the line relay.
8. In a telephone system, a plurality of groups of trunks, a switch having two incoming talking conductors and a line relay, and having access to the groups of trunks, means for operating the line relay when the incoming conductors are seized, a guarding relay, means controlled by the release relay for marking the switch busy, said release relay being controlled by the line relay, and additional means effective if a busy group of trunks is encountered to control said release relay.
9. In a telephone system, a selector having a line relay, a release relay, and a primary magnet, circuit connections controlled by the line relay for controlling the primary magnet, and means effective under predetermined conditions for substituting a winding of the release relay for the primary magnet in said circuit.
10. In a telephone system, a selector having a line relay, a release relay, and a primary magnet, circuit connections controlled by the line relay for controlling the primary magnet, and means effective responsive to a busy group of trunks being encountered for substituting a winding of the release relay for the primary magnet in said circuit.
11. In a telephone system, a plurality of switches, each switch including a line relay and a release relay, said guarding relay having two operating windings, one of which windings is controlled by the line relay in a circuit local to the switch and the other controlled over a circuit common to all of the switches.
12. In a telephone system, a plurality of groups of switches, busy signalling apparatus common to the switches, said apparatus including alarm devices through which the signals are transmitted, and means, including readily detachable connecting links, whereby any defective group of switches may be readily disconnected from the apparatus.
13. In a telephone system, a plurality of switches each having an incoming talking conductor, means common to all of the switches for applying signalling current to the talking conductor of any of the switches, said means including a low resistance alarm relay through which the signalling current is sent, and means controlled by said relay for inserting a high resistance in series with the low resistance.
14. In a telephone system, a plurality of groups of switches, each switch having a pair of incoming talking conductors, a relay device individual to each group of switches, means common to all of said devices for intermittently energizing and deenergizing said devices, and means controlled by each of said devices for supplying busy flash current to all of the switches of its group.
15. In a telephone system, a plurality of groups of switches, each switch having a pair of incoming talking conductors, a relay device individual to each group of switches, means common to all of said devices for intermittently energizing and deenergizing said devices, means controlled by each of said devices for supplying busy flash current to all of the switches of its group, and means in each switch effective under predetermined conditions to transmit said busy flash current over one of its incoming talking conductors.
16. In a telephone system, a plurality of automatic switches, each switch having two incoming talking conductors and a line relay, each switch having accessible thereto a plurality of groups of trunks, means common to all of the switches and effective responsive to any one switch encountering a busy group of trunks for signalling over at least one of the incoming talking conductors of that one switch, said means including a circuit arrangement whereby both of the talking conductors of the switch are maintained at the same electrical potential during signalling.
17. In a telephone system, a plurality of automatic switches, each switch having two incoming talking conductors and a line relay, means common to all of the switches and effective upon the occurrence of predetermined conditions in any of the switches for periodically signalling over at least one of said incoming talking conductors of the switch in which the conditions occurred, said means including circuit arrangements for maintaining both of said incoming talking conductors at the same electrical potential during signalling.
18. In a telephone system, a switch having two incoming talking conductors, a line relay controlled over said talking conductors, means at the switch for signalling over said incoming talking conductors, said means including means for periodically connecting both of said talking conductors to points of the same electrical potential through the winding of the line relay.
19. In a telephone system, a selector switch having a line relay controlled over an incoming talking conductor, a primary magnet controlled by the line relay for selecting a group of trunks, an automatically operated second-

- ary magnet for selecting an idle trunk in the selected group of trunks, a switching relay for disconnecting the line relay from the line, and means effective responsive to the failure 5 of the secondary magnet finding an idle trunk in the selected group of trunks for rendering the switching relay inoperative to disconnect the line relay and for preventing the line relay from operating the primary magnet.
- 10 20. In a telephone system, a selector switch having a line relay controlled over an incoming talking conductor, a primary magnet controlled by the line relay for selecting a group of trunks, an automatically operated secondary magnet for selecting an idle trunk in the selected group of trunks, a switching relay for disconnecting the line relay from the line, means effective responsive to the failure of the secondary magnet finding an idle trunk 15 in the selected group of trunks for rendering the switching relay inoperative to disconnect the line relay, for preventing the line relay from operating the primary magnet, and for connecting a source of signalling current to 20 an incoming talking conductor.
21. In a telephone system, a selector switch having a line relay normally connected to an incoming talking conductor, a primary magnet controlled by the line relay for causing 25 the switch to select a group of trunks, means for then causing the switch to hunt for an idle trunk in the selected group, a switching relay for disconnecting the line relay from the talking conductor, means operative upon 30 the switch's failure to find an idle trunk for short-circuiting the switching relay to prevent it from operating, and for removing the primary magnet from under the control of the line relay.
22. In a telephone system, a selector for 40 selecting an idle trunk of a group, a line relay for the selector controlled by a flow of current over the talking conductors terminating in the selector, a release relay responsive to the operation of the line relay, and means operative upon the selector's finding no idle trunk in the group for stopping the flow of current over the talking conductors, and for maintaining the release relay operated independent of the line relay. 45
23. In a telephone system, a selector for selecting an idle trunk of a group, a line relay for the selector controlled by a flow of current over the talking conductors terminating in the selector, a release relay responsive to the 50 operation of the line relay, and means operative upon the selector's finding no idle trunk for periodically stopping the flow of current over the talking conductors, and for maintaining the release relay operated independent of the line relay during each period the current over the talking conductors is stopped by the last said means. 55
